William Edward

UNITED STATES PATENT OFFICE.

MOSES M. MARCUSE, OF NEW YORK, N. Y., ASSIGNOR TO WEST DISINFECTING COMPANY,
OF NEW YORK, N. Y., A CORPORATION OF NEW YORK.

DEVICE FOR AUTOMATICALLY CLOSING THE COVER OF SEATS OF CLOSETS, COMMODES,
AND THE LIKE.

1,134,755.

Specification of Letters Patent.

Patented Apr. 6, 1915.

Application filed September 12, 1913. Serial No. 789,467.

To all whom it may concern:

Be it known that I, MOSES M. MARCUSE, a citizen of the United States, and resident of the borough of Manhattan, in the city 5 and State of New York, have invented a new and useful Improvement in Devices for Automatically Closing the Cover of Seats of Closets, Commodes, and the like, of which the following is a specification.

10 My invention relates to an improvement in a device for automatically closing the cover of seats of closets, commodes and the like.

15 The object of this invention is to provide a device that is simple, inexpensive and one that may be readily applied to the present cover and seats now in common use.

20 A further object is to provide a device that will automatically close the cover upon the seat, the closing of which being controlled by the upward movement of the seat when weight is removed therefrom.

25 A practical embodiment of the invention is represented in the accompanying drawings, in which,

Figure 1 represents a plan view of my device placed in position on a seat of a closet or commode. Fig. 2 represents a longitudinal section taken in the plane of 30 the line A—A of Fig. 1, the cover being shown raised in dotted lines. Fig. 3 represents a view of the same, the parts being shown in the position which they assume when the weight has been lifted from the 35 seat, the cover having been pushed to a position where it will close by gravity, and Fig. 4 represents a transverse section taken in the plane of the line B—B of Fig. 2.

40 The seat is denoted by 1, and is hinged at 2, to a back member 3, which is fixed to the commode 4, or other closet, by any well known and approved means.

45 A cover 5 is provided for closing upon the seat, which cover is also hinged at 2, to the back member 3. The cover has secured to its under side an annular gasket or ring of rubber or other resilient material 6, located so as to engage the seat 1 when closed and form a seal between the cover and seat, thereby preventing any odor from escaping 50 between the same.

To automatically close the cover 5 when the commode or closet is not in use, I provide means controlled by the seat 1, adapted

to engage the cover 5, which means is constructed, arranged and operated as follows: A push lever 7 is mounted to rock in a housing 8 which is secured to the back member 3, by screws 9. The push lever 7 is pivoted at 10, in the housing and has two arms 11, 12. A plunger 13 is fitted to slide vertically in the back member 3, the top of which plunger engages the arm 12, and the bottom of which plunger is adapted to be engaged by an arm 14 fixed on the seat 1. The parts 15 are so arranged that the push arm 11 of the lever 7 is normally thrown forward, in the present instance by weighting the arm 12. When the seat is down and the cover raised, the lever will be held at the limit of its 20 rearward movement by the arm 14 on the seat 1 engaging the plunger 13. When the seat is permitted to lift, it will permit the lever to rock forwardly causing the push arm 11 to force the cover forwardly past 25 center, thereby causing it to drop to its closed position, as shown in Figs. 1 and 2. The housing 8 also acts as a stop for limiting the opening movement of the cover 5. To cause the seat 1 to lift when the weight 30 of the person using it is removed, I provide springs 15 located in cups 16 in the commode or closet 4, which springs will normally only hold the seat lifted away from the commode, but when the cover is closed 35 upon the seat, the added weight of the cover will cause the seat to compress the springs until it rests upon the commode.

It is to be understood that while I have shown this device applied to a commode, it 40 is obvious that I wish to cover the same wherever it can be advantageously used.

It is evident that slight changes might be resorted to in the form, construction and arrangement of the several parts without 45 departing from the spirit and scope of my invention; hence I do not wish to limit myself strictly to the structure herein set forth, but

What I claim is:

1. A device of the character described comprising a back member, a seat hinged thereto, a cover for said seat hinged to the back member, and a weighted push lever controlled by the upward movement of the 50 seat and adapted to engage the cover for closing it.

2. A device of the character described

100

105

comprising a back member, a seat hinged thereto, a cover for said seat hinged to the back member, and means controlled by the upward movement of the seat for closing the cover, said means comprising a weighted push lever adapted to engage said cover and an arm carried by said seat for engaging said lever.

3. A device of the character described comprising a back member, a seat hinged thereto, a cover for said seat hinged to the back member, and means controlled by the upward movement of the seat for closing the cover, said means comprising a weighted push lever adapted to engage said cover, an arm carried by said seat and a plunger interposed between said lever and arm.

4. A device of the character described comprising a back member, a seat hinged thereto, means for holding the seat in a lifted position, a hinged cover for said seat, and means controlled by the upward movement of the seat for closing the cover, said means comprising a weighted push lever adapted to engage said cover, an arm car-

ried by said seat and a plunger interposed between said lever and arm.

5. A device of the character described comprising a movable seat, a cover for closing and depressing the seat, said cover being fitted to open rearwardly past center, a stop for the cover, means for normally lifting the seat when the cover is open, and means controlled by the upward movement of the seat for throwing the cover forwardly past center to permit it to drop by gravity onto said seat, said means comprising a weighted push lever housed in said stop and adapted to engage said cover, an arm carried by the seat and a plunger interposed between said lever and arm.

In testimony that I claim the foregoing as my invention, I have signed my name in presence of two witnesses, this tenth day of September 1913.

MOSES M. MARCUSE.
